UNITED STATES PATENT OFFICE.

WILBUR BENNETT, OF SCRANTON, PENNSYLVANIA, ASSIGNOR TO THE GRAFF FURNACE COMPANY, OF NEW YORK, N. Y., A CORPORATION OF NEW YORK.

DESIGN FOR A KITCHEN RANGE.

Application filed May 22, 1926. Serial No. 17,814. Term of patent 7 years.

To all whom it may concern:

Be it known that I, WILBUR BENNETT, a citizen of the United States, and a resident of Scranton, in the county of Lackawanna and State of Pennsylvania, United States of America, have invented a new, original, and ornamental Design for a Kitchen Range, of which the following is a specification, reference being had to the accompanying drawing, forming part thereof.

The figure is a perspective view of a kitchen range, showing my new design.

I claim:

The ornamental design for a kitchen range, as shown.

WILBUR BENNETT.
